E. W. SUMMERS.
DOOR ARRANGEMENT FOR DUMPING CARS.
APPLICATION FILED OCT. 8, 1908.

1,038,228.

Patented Sept. 10, 1912.

UNITED STATES PATENT OFFICE.

EDGAR W. SUMMERS, OF PITTSBURGH, PENNSYLVANIA.

DOOR ARRANGEMENT FOR DUMPING-CARS.

1,038,228.

Specification of Letters Patent. Patented Sept. 10, 1912.

Application filed October 8, 1908. Serial No. 456,809.

To all whom it may concern:

Be it known that I, EDGAR W. SUMMERS, a resident of Pittsburgh, in the county of Allegheny and State of Pennsylvania, have 5 invented a new and useful Improvement in Door Arrangements for Dumping-Cars, of which the following is a specification.

This invention relates to hopper bottom railway cars, and more particularly to the 10 door arrangement and operating mechanism therefor.

The object of the invention is to provide doors and door operating mechanism for hopper bottom cars which provide a large 15 opening for the discharge of the lading, and which enable the center of the gravity of the loaded car to be carried quite low and nevertheless permit the opening of the doors without contacting with the track.

20 The invention comprises the arrangement and combination of parts hereinafter described and claimed.

In the accompanying drawings Figure 1 is a vertical transverse section through a 25 car embodying the invention, one-half of said figure being taken at the end of a door and the other part being taken through a door, parts being broken away to more clearly show the construction; Fig. 2 is a 30 plan view, parts being broken away, of the doors and their operating mechanism; and Fig. 3 is a vertical section taken longitudinally of the car on line 3—3 Fig. 1.

The doors are shown applied to a center 35 discharge hopper car, such as an ore car, but it will be understood that it can be applied to any hopper car with the doors arranged either longitudinally or transversely. As shown in the drawings the car body is pro- 40 vided with end sloping floor plates 1, and side sloping plates 2 which narrow the body somewhat at the bottom. These sloping plates provide a very large center opening extending sidewise beyond the wheels, which 45 are shown at 3 and extending longitudinally of the car between the wheels. This pro- 50 vides a large opening for the rapid discharge of the lading, and one which prevents the lading, such as iron ore, from bridging 55 or arching over the opening. The discharge opening is closed by two doors 4 and 5 which extend longitudinally of the car and close toward the center line of the car, the specific arrangement shown having the inner edges 60 of the doors abutting, as shown in Figs. 1 and 2. The doors when closed slope in-

wardly and downwardly and are provided at their ends with vertical portions 6 which extend upwardly and are located underneath the inner edges of the end floor plates 60 1. The outer edges of the doors also are preferably turned upwardly slightly as at 7 and lie underneath the side sloping plates 2. The upturned outer edges and the up- 65 turned end portions give stiffness to the doors and the doors are further stiffened by having their inner edges flanged down- 70 wardly, as at 8, and also having secured thereto longitudinal bars, such as Z bars 9, and transverse bars 10.

To each end of the door at its outer edge is secured a roller 11 running on a guide or track 12 which curves upwardly from its inner to its outer edge. To each end at the inner edge of the door is secured a roller 13 running on a track or guide 14 which slopes downwardly from the center of the car outwardly. The tracks or guides 14 on both sides of the longitudinal center of the car are formed from a single bar bent to the 80 shape shown in Fig. 1 and having its ends riveted to a transverse plate beam 15 ex- 85 tending from side to side of the car. The intermediate portion of the guide 14 may also be supported from said beam 15, such as by a casting 16 riveted to said beam. The tracks or guides 12 have their inner 90 ends riveted to the transverse beam 15 while their outer ends are suitably secured, as at 18, to the side plates of the car. The journal pins of the rollers 11 have their inner sides mounted in a portion of the door and their outer ends mounted in straps 19 riveted to the end portions 6 of the doors. The journal pins of the rollers 13 have their inner 95 ends mounted in the end portions 6 of the doors and their outer ends supported by brackets 20 riveted to said end portions of the door and lying beyond or outside of the guides or tracks 14.

When the doors are closed, as in Fig. 1, the rollers at the inner edges of the doors are supported on the high portions of the guides or tracks 14, while the rollers at the outer edges of the doors are supported on the lower portions of the guides or tracks 12. The doors open by moving outwardly, the rollers at the inner edges running down the inclined guides or tracks 14 which are quite steep so that the doors when released fall by gravity, while the rollers at their outer edges run upwardly on the curve

guides or tracks 12, thus lifting the outer edges of the doors and permitting them to fall to open position without hitting the track. The center of gravity of the doors 5 moves downwardly so that the doors need not be pulled open, but the inner edges of the doors do not swing in the arc of circle as in the case of doors hung on hinges. The consequence is that a large discharge opening 10 may be employed and the doors may be located comparatively low and still be enabled to fully open without striking the track. This arrangement enables the center of gravity of the loaded car to be quite 15 low and at the same time gives a very large discharge opening.

Any suitable mechanism may be used for operating the doors. As shown each door has connected thereto a pair of links 22 20 whose outer ends are connected to cranks 23 or rock shafts 24 mounted in suitable bearings and located longitudinally of the car. When the cranks 23 and links 22 are brought into line as shown in full lines in Fig. 1 the 25 doors are held in closed position, while when moved to the position shown in dotted lines in Fig. 1 the doors are allowed to drop to open position. Suitable means, not shown, will be provided for locking the shafts 24 30 against accidental rotation when the doors are in closed position. To open the doors it is only necessary to release the shafts and start them in their rotary movement in order to flex the toggles formed by crank 23 35 and links 22, after which the weight of the load or of the doors themselves will force the doors to open position.

The arrangement shown can be used for discharging the load on either side or in the 40 center. For discharging at the side only one of the doors is opened, whereas to discharge in the center both doors are opened.

The door arrangement described is of 45 rather simple construction and provides a very large discharge opening by means of doors located close to the track. The arrangement furthermore insures the doors being held tightly closed, since the supports for the inner edges of the doors are rigid 50 and cannot yield.

What I claim is:—

1. A railway car provided with a bottom discharge opening, a longitudinally arranged inclined door closing toward the 55 center of the car, and guiding supports for the inner and outer edges of the door, the supports for the outer edge sloping upwardly and those for the inner edge sloping downwardly, whereby when the door is moving outwardly it assumes a greater inclination, and means for moving the door on its supports.

2. A railway car provided with a bottom discharge opening, an inclined door closing 60 toward the center of the car, and guiding

supports for the inner and outer edges of the door, said supports being located beyond the ends of the door opening and the supports for the outer edge of the door sloping upwardly and those for the inner edge sloping downwardly, and means for moving the door on said supports. 70

3. A railway car provided with a bottom discharge opening and provided with sloping body plates, an inclined door arranged to close said opening, supports for the inner and outer edges of the door located underneath the sloping body plates, the supports for the outer edge of the door sloping upwardly and those for the inner edge of the 75 door sloping downwardly, and means for moving the door on said supports. 80

4. A railway car having a bottom discharge opening and provided with sloping end floor plates, a longitudinally arranged 85 inclined door closing toward the center of the car, and guiding supports for the outer and inner edges of the door and located underneath the sloping end floor plates, the guides for the outer edge of the door sloping 90 upwardly and those for the inner edge of the door sloping downwardly, and means for moving the door on said guides. 95

5. A railway car having a bottom discharge opening, a longitudinally arranged 100 door closing toward the center of the car, transverse beams at the ends of the door opening, guides for the outer and inner edges of the door on said transverse beams, the guides for the outer edge of the door 105 sloping upwardly and those for the inner edge of the door sloping downwardly, and means for moving the door on said guides. 110

6. A railway car provided with a bottom discharge opening, doors closing said opening 115 and having their edges contacting when closed and being lower at the contacting edges than at the outer edges, and supports on which said doors are movably mounted, said supports being arranged to permit the 120 doors to move apart and simultaneously lower their meeting edges and elevating their outer edges.

7. A railway car having a bottom discharge opening, doors closing said opening 115 and having their meeting edges when closed lower than their outer edges and having upturned end portions higher at the meeting edges of the door than at the outer edges, sloping body plates under which said upturned edges close, and guiding supports for said doors arranged to permit the doors to move apart and simultaneously lower their meeting edges and elevate their outer edges. 125

8. A railway car having a bottom discharge opening, doors closing said opening and having their meeting edges when closed lower than their outer edges, and guides or tracks on which said doors are movably 130

mounted, said guides or tracks being so arranged that as the doors move apart their meeting edges are lowered.

9. A railway car provided with a bottom discharge opening, a longitudinally arranged inclined door closing toward the center of the car, and tracks or guides on which the inner and outer edges of the door are supported and on which the door moves, the tracks or guides for the inner edge of the door sloping downwardly and outwardly, whereby when the door is moved outwardly it assumes a greater inclination, and means for moving the door on said tracks or guides.

10. A railway car provided with a bottom discharge opening and with sloping end floor plates, a longitudinally arranged inclined door closing toward the center of the car, and guides or tracks for the ends of the doors located beyond the ends of the door opening, the guides or tracks for the inner edge of the door sloping downwardly and outwardly, and means for moving the door on said guides or tracks.

11. A pair of doors for dump cars movable bodily and inclined and closing together at their lower edges, oppositely inclined supporting means positioned beneath the center of the car for the inner portions of the doors, oppositely inclined supports at opposite sides of the car for the outer portions of the doors, and door actuating means.

12. An inclined rolling door for dump cars mounted to roll toward open position without raising its center of gravity, and mechanism for rolling the door.

13. An inclined bodily movable door for dump cars mounted in opening to move

transversely of the car and to vary its inclination while moving without raising its center of gravity, and door moving mechanism.

14. An inclined bodily movable door mounted in opening to move transversely of the car, and means for increasing the inclination of the door while opening without elevating any part thereof while in contact with the material being dumped.

15. An inclined bodily movable door for a dump car mounted in opening to move transversely of the car to lower its center of gravity while opening, and door moving mechanism.

16. An inclined rolling door for dump cars mounted to lower its center of gravity while opening, and mechanism for rolling the door.

17. A bottom for car hoppers consisting of oppositely inclined doors meeting at their lowermost edges, means for moving each of said doors bodily away from the other, and means for increasing the inclination of the doors as they move apart without raising their centers of gravity.

18. In a bottom for car hoppers, a bodily movable door inclined when closed, supports over which the higher and lower portions of the door move and arranged to increase the inclination of the door while opening, and actuating means connected to the door above its lowermost portion.

In testimony whereof I have hereunto set my hand.

E. W. SUMMERS.
